UNITED STATES PATENT OFFICE.

GEORGE B. HOWLAND, OF CHICAGO, ILLINOIS.

DESIGN FOR A GATE-LATCH.

SPECIFICATION forming part of Design No. 34,279, dated March 26, 1901.

Application filed February 20, 1901. Serial No. 48,194. Term of patent 14 years.

To all whom it may concern:

Be it known that I, GEORGE B. HOWLAND, a citizen of the United States, and a resident of Chicago, in the county of Cook and State 5 of Illinois, have invented and produced a new and original Design for Gate-Latches, of which the following is a specification.

In the drawings, Figure 1 is a side view of the latch made according to my design. Fig. 10 2 is a side edge view of the same. Fig. 3 is an end edge view thereof.

The important feature of my invention is the double-heart shape given the latch.

The drawings illustrate a latch of suitable 15 thickness, which consists of two heart-shaped ends *a a*, which align with each other and are arranged so that their apexes point in opposite directions. These ends *a* are connected by a central bar *b* of suitable length, which,

about its center, is provided with a pivotal opening. The lobes *c c* of the heart-shaped ends are considerably narrower than the lobes of a perfect heart-shaped figure. The narrowness of the lobes and the relative distance apart of said ends *a* make a recess *d* in the 25 edges of the latch at the center of length thereof on each side of the pivotal opening, the opposing sides of which are undercut, as shown.

What I claim as new, and desire to secure 30 by Letters Patent, is—

The design for a gate-latch as shown and described.

GEORGE B. HOWLAND.
